UNITED STATES PATENT OFFICE.

JOHN FISH, OF SOUTH BEND, INDIANA.

CONCRETE-MIXER.

No. 892,239.

Specification of Letters Patent. Patented June 30, 1908.

Application filed June 29, 1907. Serial No. 381,542.

To all whom it may concern:

Be it known that I, JOHN FISH, a citizen of the United States, residing at South Bend, in the county of St. Joseph and State of Indiana, have invented certain new and useful Improvements in Concrete-Mixers, of which the following is a specification.

This invention relates to concrete mixers.

One object of the invention is to provide a concrete mixer embodying such characteristics that it will automatically measure and deliver the materials mixed in their proper proportions to the mixing chamber.

Another object resides in the provision of a concrete mixer so constructed and arranged that the mixing cylinder may be adjusted to different inclinations in its longitudinal direction to control the speed or gravity of the concrete mixture in its discharge from the cylinder.

A still further object of the invention is to provide a continuous concrete mixer whose parts are so associated in their coöperative relations that positiveness and effectual operation results both in the mixing of the materials together and in the discharge of the mixed materials from the machine.

With the above and other objects in view the present invention consists of the combination and arrangement of parts hereinafter more fully described, illustrated in the accompanying drawings, and particularly pointed out in the appended claims, it being understood that changes may be made in the form, proportion, size and minor details, without departing from the spirit or sacrificing any of the advantages of the invention.

In the drawings:—Figure 1 is a side elevation of the invention. Fig. 2 is a view illustrating the invention partly in plan and partly in horizontal section. Fig. 3 is a vertical sectional view on the line $x-x$ of Fig. 1. Fig. 4 is a vertical sectional view on the line $y-y$ of Fig. 1. Fig. 5 is a sectional view of the hopper including the measuring roller and chute. Fig. 6 is a fragmentary view of one end of the combined feeding and measuring roller illustrating the filling of one or more of the pockets thereof to regulate the measuring of the materials in different proportions.

Referring now more particularly to the accompanying drawings it will be seen that for a support for the machine there is provided spaced pairs of legs 1 and 2, each having uprights 3 secured at their upper ends to form guide ways for the guidance of the adjustable

frames 4, in which are carried bearings 5 and in which latter is journaled the part 6 of the drive shaft which coöperates, in a manner hereinafter explained, with the part 7 of the drive shaft. These frames 4 are adjusted vertically in the respective guide ways by the screw bolts 8, and in the event that the frame 4 is adjusted vertically at the outer end of the machine while the frame 4 at the inner end thereof is held against adjustment, the mixing cylinder 9 which is keyed to the part 6 of the drive shaft, may be inclined according to the inclination of the drive shaft incident to the vertical adjustment of the frame 4 at the outer end of the machine, the said bearings being pivoted in the frames 4 by the pivot bolts 10.

To permit of the adjustment of the mixing cylinder 9 to different inclined positions in its longitudinal direction, is the reason why the drive shaft is formed of the two parts 6 and 7. If the frame 4 at the inner end of the machine remains fixed while frame 4 at the outer end of the machine is adjusted vertically, the spaced bearings 11 of the bracket 12 secured to the inner legs 2 would prevent such adjustment of the mixing cylinder unless the drive shaft was formed in two parts. For this reason there is fixedly secured to the inner end of the part 6 of the drive shaft a disk 13 which carries lateral projections 14 which project through the slots 15 of a disk 16 carried at the inner end of the part 7 of the drive shaft. These slots 15 of the disk 16 permit of sufficient play of the lateral projections 14 as to provide for a universal coupling between the parts 6 and 7 of the drive shaft, so that the mixing cylinder may be driven at varying angles to the drive shaft. Thus it will be understood that the part 6 of the drive shaft of the mixing cylinder is journaled at both ends in bearings which are pivotally supported in vertically adjustable frames, whereby the pivotal bearings of the part 6 of the drive shaft will permit the bearings to assume the same angle as the part 6 of the shaft, when the latter is adjusted to an angle with relation to the part 7 of the drive shaft. The drive shaft may be driven from any suitable source, but I illustrate in the drawings the pulleys 17 with which may be connected one or more belts operated from a driving mechanism. (Not shown.)

Mounted at the top of the inner one of the guide ways 4 is a hopper 18 provided with a measuring roller 19 adapted to regulate the

quantity of material passing through the hopper, the materials in their passage through the hopper being controlled by the measuring roller 19, and when so controlled are discharged into the chute 20, as shown in Fig. 2, the chute being preferably curved and narrower at its discharge end than at its inner end.

The chute is preferably open at its top so that water from the water tank 21 supported by brackets 22 of the machine may be lead into the chute to moisten the materials by means of the nozzle 23 which has connection with the tank 21 through the valve pipe 24.

15 By reason of the valve pipe 24 the water may be supplied in the proper proportions.

The measuring roller 19 is mounted upon a shaft 25 which has a sprocket 26, whereby, through the instrumentality of a chain 27 leading from the sprocket 28 of the part 7 of the drive shaft, the combined feeding and measuring roller may be operated by and with the drive shaft.

In the compounding of concrete compositions, the materials must be properly proportioned so that the feeding of one material with relation to another may be proportioned according to predetermined ratios. For this reason, the hopper 18 is preferably divided into two compartments 29 and 30 by means of the partition 31 as best shown in Figs. 2 and 5. The combined feeding and measuring roller 19 has formed in its periphery recesses adapted to form pockets 32 for the reception of the materials placed within the hopper. On one end of the combined feeding and measuring roller 19 there is provided a greater number of pockets 32 than the number of pockets upon the opposite end thereof, 40 the pockets at one end of the roller being arranged for coöperation with the compartment 29 of the hopper and the pockets at the opposite end of the roller being arranged for coöperation with the other compartment 45 30 of the hopper. This arrangement of a greater number of pockets at one end of the roller than at the other end thereof is to permit of the feeding of one ingredient with relation to the other, as for instance cement 50 and sand, so that the former may be in proportion with the latter and produce the required ratio as for instance one to nine or one to two, or one to one, as may be required. This regulation of the quantity of 55 one material with relation to another may be accomplished by providing the measuring rollers with the required sizes and numbers of pockets, or by placing a block 33 in one or more of the pockets at either end of the 60 measuring roller, as shown in Fig. 6 to cut out any required number of pockets. In Figs. 3 and 4 of the drawings, the pockets for the cement or other material are three in number and for the sand or other material 65 nine in number, so that in one revolution of

the combined feeding and measuring roller, one part of cement to three parts of sand will be delivered to the chute 20, and by means of the water tank and its connections the materials thus mixed may be dampened according to conditions or requirements.

After the mixture is delivered to the mixing cylinder it is rapidly carried upward by the blades 34, (see Fig. 2) and falls on the bottom of the cylinder as it reaches the top 75 of the latter and then slowly gravitates to the discharge end of the cylinder.

From the foregoing it will be seen that there is provided in this invention a continuous mixer, as the material is being continuously fed in proper proportions and discharged into the mixing cylinder, and without any attention from the operator except to see that the hopper is kept supplied with material to be mixed.

85 What is claimed is:—

1. In a device of the class described supporting elements having spaced guide ways, frames mounted for vertical adjustment in said guide ways, a shaft in two parts with 90 one part mounted for rotation in said supporting element and the other part mounted for rotation in said frames, a flexible connection between the two parts of the shaft, a mixing cylinder carried by one part of said shaft, and driving means applied to the other part of said shaft.

2. In a device of the class described, supporting elements having spaced guide ways, vertically adjustable frames carried by said guide ways, bearings pivotally supported in said frames, a shaft in two parts with one part mounted for rotation in said supporting element and the other part mounted for rotation in said bearings, a flexible connection between the parts of said shaft, a mixing cylinder carried by one of said shafts, and driving means applied to the other of said shafts.

105 3. In a concrete mixer the combination 110 with supporting elements, a drive shaft mounted in said elements composed of two parts, a mixing cylinder carried by one part of the shaft, a connection between the parts of the shaft, one part of the shaft being adjustable independently of the other part thereof, a hopper, a combined feeding and measuring roller mounted in the hopper, a chute coöperatively arranged between the combined feeding and measuring roller and the mixing cylinder, a water tank, means coöperating with the water tank to deliver water to the chute in regulated quantity, and means whereby the drive shaft and combined feeding and measuring roller may 120 be operated simultaneously.

125 4. In a device of the class described supporting elements, vertically adjustable frames mounted in guide ways on said supporting elements, a shaft in two parts with one part 130

- mounted for rotation in said supporting element and the other part mounted for rotation in said vertical frames, a flexible connection between the parts of said shaft, a mixing cylinder carried by one part of said shaft, a driving means applied to the other part of said shaft, means for feeding material to said cylinder, and means whereby the driven shaft and feeding means are operated simultaneously.
5. In a device of the class described supporting elements comprising spaced standards having spaced vertical side members and with a bracket extending from one member and provided with bearings, frames 30 movable vertically between said side members, means carried by the standards for adjusting said frames, a drive shaft in two parts with their adjacent ends confronting, one part journaled in said bracket bearings 35 and the other part of said shaft journaled through said frames, a flexible coupling between said shaft parts, a mixing cylinder carried by one part of said shaft, and operating means applied to the other part of 40 said shaft.
10. 5. In a device of the class described supporting elements comprising spaced standards having spaced vertical side members and with a bracket extending from one member and provided with bearings, frames 45 movable vertically between said side members, means carried by the standards for adjusting said frames, a drive shaft in two parts with their adjacent ends confronting, one part of said shaft journaled in said bracket bearings 50 and the other part of said shaft journaled through said frames, a flexible coupling between said shaft parts, a mixing cylinder carried by one part of said shaft, and operating means applied to the other part of 55 said shaft.
6. In a device of the class described supporting elements comprising spaced standards having spaced vertical side members and with a bracket extending from one member and provided with bearings, frames 30 movable vertically between said side members, means carried by the standards for adjusting said frames, a drive shaft in two parts with their adjacent ends confronting, one part journaled in said bracket bearings 35 and the other part journaled through said frames, disks upon the confronting ends of said shaft parts with radial apertures through one of said disks and pins extending from the other disk and through said apertures, a mixing cylinder carried by one of said shaft parts, 40 and an operating means applied to the other shaft part.

In testimony whereof I have signed my name to this specification in the presence of 45 two subscribing witnesses.

JOHN FISH.
